FOLDING INFANT'S CHAIR

Joseph W. Cox and Joseph Cox, Jr., Bronx, N. Y.

Application December 8, 1945, Serial No. 633,766

2 Claims. (Cl. 155—78)

1

This invention relates to an improved folding or collapsible chair for infants, and one of its objects is to provide a chair with means for detachably connecting the same to the side of a table, so that the chair and an infant may be supported on the side of the table.

Another object is to provide an infant's chair with a frame which is arranged to fold or collapse, so that it may be stored away in a small space.

A further object of the invention is the provision of a folding infant's chair with a seat which is hinged over a base having a service opening therein, so that the seat may be raised when the infant is required to perform a natural function.

With the above and other objects in view, the invention comprises certain new and useful constructions, combinations, and arrangements of parts, clearly described in the following specification, and fully illustrated in the accompanying drawings, in which:

Fig. 1 is a perspective view, showing the chair before it is connected in place on the side of a table.

Fig. 2 is a side elevation, on a smaller scale, showing the chair supported on the side of the table.

Fig. 3 is a transverse sectional view, taken on line 3—3 of Fig. 2, looking in the direction of the arrows.

Fig. 4 is a side elevation showing the chair supported by a detachable bracket on the side of a table.

Fig. 5 is a top plan view thereof.

Fig. 6 is a perspective view of the bracket shown in Fig. 4.

Referring to the accompanying drawing, which illustrates the practical embodiment of the invention, 5 designates a base board having a large service opening 6 therein. To the upper side of this base board the solid or imperforate seat 7 is connected at its rear edge by the hinges 8, so as to fold upwardly and rearwardly.

On each side of the base 5 a steel frame bar is arranged, one bar 9 extends along the side of the base 5 and is pivotally connected at its rear end at 10 to the lower corner portion of the back 11. The bar 12 on the opposite side is pivotally connected to the opposite lower corner of the back 11. The base 5 is secured to the bars 9 and 12 by screws 5' near the rear end of the bars. At a point opposite or near the forward corner of the base 5, the steel bar 9 is pivotally connected by the rivet 13 with the lateral steel

2

bar 14 which rivet 13 secures the bar 9 to the base 5. A diagonal brace bar 15 is also pivotally connected at its forward end with the rivet 13 and is secured by the screw 16 to the side of the back 11, at a point above the lower corner thereof, and nearer the top edge thereof.

The upper end of the lateral bar 14 is pivotally connected by the rivet 17 with the upper side steel bar 18, the rear end of which is connected to the screw 16 on the back 11. A wing nut 19 is threaded on the screw to hold the steel bar 18 and the diagonal brace 15 clamped on the screw, when the chair is in an open position. The bar 12 is similarly pivotally connected to the lateral bar 20, and the upper end of this lateral bar is pivotally connected by a rivet 20' with the upper side bar 21, the rear end of which is connected to the side of the back 11, together with the rear end of the diagonal brace 22, the forward end of which is pivotally connected to the lower end of the lateral brace or bar 20 and to the bar 12, in the manner previously described with reference to the bars 9, 14 and 15. The connection between the brace 22 and the upper side bar 21 is tightened by means of the wing nut 23.

The lower side bars 9 and 12 are extended forwardly of the base 5, and are provided with twisted portions 9a and 12a, and flat terminal arms 9b and 12b, which have upstanding stops 9c and 12c thereon. The forward ends of the upper side bars 18 and 21 are similarly constructed, to provide flat arms 18a and 21a, which terminate in stops 18b and 21b.

To the lateral bar 14 the upper end of the link bar 24 is pivotally connected at 24a, and to the lateral bar 20 the upper end of the link 25 is pivotally connected at 25a. The lower ends of these links are pivotally connected with the foot board 26.

The upper side arms 18 and 21 are engaged with the top edge of the side board 27 of a conventional table, as shown in Fig. 2, and the end stops 9c and 12c of the lower arms 9 and 12 are engaged with the outer face of this board.

Access to the upper edge of the board 27 is obtained by raising the table top which may be hinged or removable. When supported in this manner the entire chair may be disconnected from the table by raising the upper arms from the side board 27. By disconnecting the upper ends of the diagonal braces 15 and 22 the entire chair may be collapsed or folded upon itself.

In Figs. 4, 5 and 6 we show a modified form of the invention, wherein the chair is supported on a pair of metal brackets 30, which are mounted

on the side board 32. Each bracket includes a central wall 33, opposing vertical side flanges 34 and 35, and an L-shaped hook flange 36, on the upper edge of the central wall 33. The side flanges 34 and 35 are formed with opposing upper notches 38 and opposing lower notches 39. The upper notches 38 are engaged by the terminal pins 40 of the upper side bars 18' and 21', and the lower notches are engaged by the terminal pins 41 of the lower side bars 9' and 12', which thus support the foldable chair in extended horizontal position, due to the parallel linkage of the upper and lower side bars of the chair, with the cross or lateral bars and the back rest.

In this construction the chair may be disconnected by merely lifting the side bars from the brackets, and these brackets may be left in place on the table for repeated future use.

It is understood that various adjustments and changes in the details of construction, their combination and arrangement may be made, within the scope of the invention, as defined by the claims hereof.

Having described the invention, we claim as new:

1. A folding infant's chair, comprising a base, a seat supported by the base, a pair of parallel side bars on each side of the base and so arranged that one lower side bar is located on the level of the base and the other upper side bar of the same pair is located above the same, a back rest pivotally connected to the rear ends of all said side bars, means for connecting the lower side bars to the sides of the base, lateral bars pivotally connected to the upper side bars and to the lower side bars, respectively, diagonal braces extending from the rear ends of the upper side bars to the lower side bars at the points of their connection with the base and means for connecting and disconnecting, respectively, the rear end of the braces from the respective side bars, so that upon disconnecting one end of the braces the upper side bars and the back rest may be turned down substantially to the level of the seat, said upper side bars having downwardly extending hooks adapted to be seated over the side board of a table with a movable top and said

lower side bars having bent ends for engaging with the face of the side board.

2. A folding infant's chair, comprising a base, a seat supported by the base, a back rest therefor, an upper and lower side bars on each side of the base, pivot means connecting the rear ends of the upper side bars to the back rest, means for connecting the lower side bars to the seat base, diagonal braces extending from the rear ends of the upper side bars to the lower side bars at the points of their connection with the base, lateral bars pivotally connected to the upper side bars and to the lower side bars, means for connecting and disconnecting, respectively, the rear end of the braces from the respective side bars, so that upon disconnecting one end of the braces the upper side bars and the back rest may be turned down substantially to the level of the seat, downwardly projecting hooks on the forward ends of the upper side bars, the downwardly projecting hooks being adapted to engage the upper edge of the side board of a table with a movable top, and upwardly projecting hooks on the lower side bars the upwardly projecting hooks being adapted to have abutting engagement with the outer face of said side board.
